CLAIM

The ornamental design for a mobile phone as shown and described.

DESCRIPTION

FIG. 1 is a front view of a mobile phone shown in a first embodiment;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a perspective view thereof;

FIG. 8 is a front view of the mobile phone shown in a second embodiment;

FIG. 9 is a back view thereof;

FIG. 10 is a left view thereof;

FIG. 11 is a right view thereof;

FIG. 12 is a top view thereof;

FIG. 13 is a bottom view thereof;

FIG. 14 is a perspective view thereof;

FIG. 15 is a front view of the mobile phone shown in a third embodiment;

FIG. 16 is a back view thereof;

FIG. 17 is a left view thereof;

FIG. 18 is a right view thereof;

FIG. 19 is a top view thereof;

FIG. 20 is a bottom view thereof;

FIG. 21 is a front perspective view thereof;

FIG. 22 is a rear perspective view thereof;

FIG. 23 is a front view of the mobile phone shown in a fourth embodiment;
 FIG. 24 is a back view thereof;
 FIG. 25 is a left view thereof;
 FIG. 26 is a right view thereof;
 FIG. 27 is a top view thereof;
 FIG. 28 is a bottom view thereof;
 FIG. 29 is a front perspective view thereof; and,
 FIG. 30 is a rear perspective view thereof.
 The broken lines depict portions of the mobile phone that form no part of the claimed design.

1 Claim, 22 Drawing Sheets

Related U.S. Application Data

having an international filing date of Jul. 20, 2022, now Pat. No. Des. 1,013,671.
